UNITED STATES PATENT OFFICE.

FREDERICK K. LANDGRAF, OF CRAFTON, AND EDWARD S. FITZ SIMMONS, OF PITTSBURGH, PENNSYLVANIA, ASSIGNEES TO FLANNERY BOLT COMPANY, OF PITTSBURGH, PENNSYLVANIA, A CORPORATION OF DELAWARE.

POT.

Application filed March 27, 1928. Serial No. 265,012.

Our invention relates to pots, and more particularly to pots for heat treating or carburizing metallic objects, although it is to be understood that the pots may be used for 5 other purposes.

The heat treating or carburizing of metallic objects is usually conducted at high temperatures in pots of a heat resisting alloy. Alloys frequently used for such purposes 10 contain chromium, iron and nickel. For heat treating various objects a salt bath is often used in the pot and for certain carburization processes it is desirable to fill the pot with a cyanide bath. When this is done 15 it is frequently found that the heated or molten chemical baths in the pot, together with the air which comes in contact with the bath, have a corrosive action upon the wall of the pot.

20 Substantially pure iron, such as wrought iron, ingot iron or steel of extremely low carbon content is resistant to the action of alkalies. Consequently, a pot of very pure iron has been used for containing cyanide 25 and other baths of an alkaline nature.

However, at the high temperatures at which such baths are maintained, an iron pot which comes in contact with the air gradually rusts away until the walls become 30 so thin as to render the pot unserviceable. The deterioration of such iron pots from outside oxidation is relatively rapid and they last only a comparatively short time.

It has heretofore been proposed to provide 35 an inner section of the pot of substantially pure iron and an outer section of a heat resistant alloy. The sections are made separately and fitted together. Difficulty has been experienced in shaping and assembling 40 the separated sections as small imperfections in the shape of either section are apt to prevent the sections from fitting snugly together when assembled.

We provide a pot and cover one or both 45 of the surfaces of the pot with a protecting layer of metal deposited by a welding operation. By welding the layer of covering metal to the pot, the covering layer conforms to the shape of the pot and does not require 50 any previous efforts to insure against minor irregularities being present in the shape of the pot. The covering and protecting layer is welded to the inner surface or the outer

surface of the pot, as may be desired, in accordance with the nature of the metal 55 used in the pot.

Where the pot is of a heat resisting alloy the interior is covered with a protective layer that is resistant to the action of the bath which the finished pot is designed to 60 contain. Where the pot is made of a material that is resistant to the action of the bath the outer surface is covered with a layer of welded material to protect it against the action of the surrounding gases at high 65 temperature. Also both the inner and outer surfaces of the pot may be covered.

The accompanying drawings illustrate certain preferred embodiments of the invention in which Figure 1 is a sectional view 70 of a pot having a protective layer deposited on the outer surface thereof.

Figure 2 is a similar view showing a protective layer deposited on the inner surface of the pot, and

75 Figure 3 is a similar view showing protective layers deposited on both the inner and outer surfaces of the pot.

Referring to Figure 1, a pot 2 resistant to the action of a bath 4 contained therein 80 is provided with an outer protective layer 5 of material resistant to the action of the surrounding air and other gases at the temperature at which the pot is operated. Where the bath 4 is of an alkaline nature, 85 such as cyanide, the pot 2 is of substantially pure iron, such as wrought or ingot iron, or steel of extremely low carbon content. Alloys suitable for the protective layer 5 contain chromium, iron and nickel.

90 By applying the protective layer 5 to the pot 2 either by machine or by a hand welding process, the protective layer conforms to the shape of the pot 2 and eliminates the trouble and expense heretofore required for 95 insuring that an inner or outer pre-shaped covering for a pot conform to and fit snugly with the adjacent surfaces of the pot. The dissimilar metals are united by a thin layer of an alloy of the metals, which makes a 100 bond between the metals. The bond prevents the separation of the metals during repeated heating and cooling cycles by reason of their different coefficients of 105 expansion.

Referring to Figure 2, a pot 6 of heat

resistant material is provided with a welded inner lining 7 of substantially pure iron that is resistant to the action of the bath 8.

Referring to Figure 3, a pot 9 of any suitable grade of metal is provided with a welded external protective layer 10 of a heat resistant alloy and it is also provided with a welded internal lining 11 of substantially pure iron that is resistant to the action 10 of an alkaline bath 12.

While we have shown the several protective layers 5, 7, 10 and 11 as being applied to their associated pots in circumferentially extending series of united beads of metal deposited by the welding operation, it is to be understood that they may be applied in substantially longitudinally extending series of united beads.

While we have shown and described the invention in connection with the heat treating or carburization of metallic objects, it is to be understood that the invention is capable of application to other processes by suitably selecting the metals and alloys comprising the pot and protective layer or layers. It is to be understood that various changes may be made in the invention without departing from the scope of the appended claims.

20 We claim:

1. A pot having a bottom of substantially semi-spheroidal contour comprising a portion resistant to the action of an alkaline bath, and a portion resistant to the action 35 of heat at the operative temperature of the

bath, one of said portions comprising a plurality of united beads of material deposited by a welding operation.

2. A pot having a bottom of substantially semi-spheroidal contour comprising an inner portion composed of a metallic material resistant to the action of a bath and an outer portion resistant to the action of heat, one of said portions consisting of united beads of welded material. 40

3. A pot for holding a bath to be heated comprising inner and outer layers of dissimilar metals resistant to the action of an erosive bath and to the action of heat, respectively, one of said layers being formed 50 in situ by united beads of metal deposited by a welding operation.

4. A pot for holding a bath to be heated comprising inner and outer layers of dissimilar metals resistant to the action of an erosive bath and to the action of heat, respectively, one of said layers being formed 55 in situ by molten metal deposited by a welding operation.

5. A pot for holding a bath to be heated comprising inner and outer continuous impervious layers of dissimilar metals resistant to the action of an erosive bath and to the action of heat, respectively, one of said 60 layers being formed in situ by united beads 65 of metal deposited by a welding operation.

In testimony whereof we have hereunto set our hands.

FREDERICK K. LANDGRAF.
EDWARD S. FITZ SIMMONS.
